UNITED STATES PATENT OFFICE.

WILLIAM HENRY GRIFFIN, OF NEW BOSTON, TEXAS.

DISPENSING-COUNTER.

1,249,617.

Specification of Letters Patent.

Patented Dec. 11, 1917.

Application filed March 20, 1917. Serial No. 156,064.

To all whom it may concern:

Be it known that I, WILLIAM HENRY GRIFFIN, a citizen of the United States, residing at New Boston, in the county of

5 Bowie and State of Texas, have invented a new and useful Dispensing-Counter, of which the following is a specification.

The present invention appertains to dispensing devices, and aims to provide a novel 10 and improved dispensing counter or cabinet for use in grocery stores and elsewhere for dispensing coffee, peas, beans and kindred materials.

It is the object of the invention to provide 15 a structure of the nature indicated which enables the various materials to be readily dispensed and weighed, to effect a saving in time and labor, the present device being comparatively simple and inexpensive in construction as well as being convenient and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made 25 within the scope of what is claimed without departing from the spirit of the invention.

The invention is illustrated in the accompanying drawing, wherein:—

Figure 1 is a rear view of the dispensing 30 counter, portions being broken away and shown in section.

Fig. 2 is a cross section taken on the line 2—2 of Fig. 1, portions being shown in elevation.

40 The counter or cabinet proper is in the form of a horizontally elongated casing, constructed of wood or other suitable material, and having the end walls 1 which can be seated upon the floor or other support. The 45 casing has a vertical front wall 2, the top 3, and inclined rear wall 4, said rear wall being inclined outwardly. The casing is provided at suitable spaced points between its ends with partitions 5 separating the casing 50 into a series of bins for holding the various materials. Each bin has a V-shaped bottom 6 sloping rearwardly, and the rear wall 4 has a discharge opening 7 for each bin located at the lower forward end of the bin bottom 6. The top 3 of the casing has a door 8 for each bin, whereby the bins can be readily filled, and the front wall 2 has a glass window 9 for each bin, whereby the customers can observe the various materials and make their selection. 60

The discharge of the material from each bin is controlled by a vertically slidable valve 10 arranged to cover and uncover the discharge opening 7, said valve being secured to the lower end of a rod 11 slidable in staples or other guides 12 secured to the rear wall 4. The upper end of each rod 11 is provided with a rearwardly projecting handle 13 near the top of the counter or cabinet, which can be readily manipulated 70 by the clerk or salesman.

The valves 10 are located near the bottom of the counter, while the rods 11 extend upwardly therefrom to enable them to be conveniently raised and lowered. 75

Carried by the top 3 of the counter longitudinally thereof is a track disposed above the inclined rear wall 4 and constituting rails 14 on which a platform scales 15 is movable, said scales having wheels 16 traveling on the rails, whereby the scales can be readily shifted longitudinally from one bin to another. 80

A hanger 17 is used for suspending a receptacle from the scales. This hanger embodies parallel vertical hanger members or bars 18 connected at their upper ends to a horizontal forwardly projecting plate 19 which rests upon the platform of the scales. The bars 18 are provided at their lower ends 85 with a forwardly projecting secondary platform 20 below the rear wall 4 of the counter, and adapted to support a cup or receptacle 21 or a scoop, or the like, which will be disposed vertically below the platform 90 of the scales whereby the weight of the material in the receptacle will be properly imposed on the platform of the scales. By the provision of the hanger 17, the receptacle 21 is supported for movement along the lower 95 edge of the rear wall 4 past the several discharge openings 7, and the receptacle will be supported, so that when the scales and hanger 17 are stopped, at any one bin, the receptacle will be in a position to receive the 100 material from the respective opening 7 when the valve 10 thereof is slid open upwardly. 105

When it is desired to take a desired quantity of material from any bin, the scales 15 is shifted upon the track until it is brought 110 over the selected bin, with the rod 11 intermediate the bars 18 when looking from the

rear, as seen in Fig. 1. This will bring the receptacle 21 below the outlet opening 7 of the selected bin, and then by reaching in between the bars 18 and raising the handle 13, the valve 10 will be opened. When the desired amount of material is discharged into the receptacle, the beam of the scales will rise, and the valve 10 is then lowered to shut off the flow of material. The receptacle can then be removed from the platform 20 for dumping the material into a bag. By having the rear wall 4 of the counter inclined, the track for the scales overhangs the lower discharge outlets of the bins, in order that the receptacle 21 can be disposed vertically below the scales, the plate 19 and platform 20 extending in the same direction to rest upon the scales platform and support the receptacle 21, respectively. The slotted formation of the hanger 17 enables the same to be readily brought to the proper position, as seen in Fig. 1.

It is preferable to provide vertical partitions 9' within the bins adjacent to the front walls thereof and immediately in rear of the windows 9, whereby to provide pockets for holding samples of the various materials so that they can be seen through the window, the materials remaining in said pockets and not being disturbed by the discharge of the materials from the bin, unless the partitions 9' are raised to permit the materials to run from the pocket. The par-

titions 9' can be lifted out of the bins through the openings in the top of the casing when the doors 8 are removed, whereby the windows can be cleaned on the inside.

It is also preferable to provide forwardly opening compartments 22 underneath the bins for holding vegetables, nails, or various other articles to which access can be had from in front of the counter, the bottoms of said compartments sloping rearwardly to retain the articles therein.

Having thus described the invention, what is claimed as new is:—

A device of the character described embodying a series of bins having lower discharge means, a platform scales movable longitudinally over the bins above the discharge means, and a hanger having a rigid plate at its upper end extending in one direction to rest upon the platform of said scales and having a rigid platform at its lower end projecting in the same direction to support a receptacle below the scales and discharge means for receiving materials from said discharge means.

In testimony that I claim the foregoing as my own, I have hereto affixed my signature in the presence of two witnesses.

WILLIAM HENRY GRIFFIN.
